FRANK E. NODINE, OF MEADVILLE, PENNSYLVANIA

LOCKING MEANS

Application filed June 2, 1931. Serial No. 541,556.

This invention relates broadly to interlocking clasps and associated fasteners such as are disclosed in British Patent No. 14,358 of June 19, 1912; and in particular to a locking device which has as its purpose the prevention of accidental displacement of the clasps once they are in engagement.

During the past few years commercial use of devices of the foregoing type has increased 10 enormously. The general structure is used in connection with shoes, over-shoes, pouches, bags, pocket-books, and more recently with garments of various kinds. Other uses are being conceived almost daily, and it may be 15 said that the device has been found practicable in conjunction with any article of apparel where there are opposed edges of an opening which must be securely closed at times, and readily and quickly opened at 20 others. These requirements have demonstrated the necessity of providing a locking means which will insure the clasps remaining in engagement, but which may at the same time be easily rendered inoperative as a lock 25 when it becomes desirable or necessary to disengage the clasps preparatory to spreading the opposed edges carrying the clasps.

To meet this need, locking devices of various types have been devised, the ordinary 30 kind consisting of supplemental members attached to a slide fastener and engageable with interlocking clasp elements. With such a lock it is necessary for the operator of the device to specially manually actuate such locking means in order to positively engage the clasps when the need for locking arises, and conversely, to specially release the lock when the need for unlocking arises.

Some of the obvious objections to previous 40 devices of this sort lie in the extra manipulation required to make them effective, the time consumed in so doing, and the possibility of the operator's forgetting to actuate the locking means; the consequences of such omission vary of course with a particular situation.

An object of this invention is to provide a simple, positive, and effective, automatic locking means.

Another object is to provide a device which

by elimination of separately moving parts, will effect economy in construction and yet which will retain all the advantages of the more complicated locking devices now in use.

A further object is to provide a locking means which automatically disengages itself when it is necessary to open or unfasten the article or garment to which the fastener is attached, thereby saving time and trouble in so opening said article or removing said garment.

These and other objects made apparent throughout the further description of my invention are achieved by means of my locking device, which I shall now explain in connection with the drawing herein, in which:

Figure 1 is a fragmental plan view illustrating an embodiment of my invention and showing some of the locking clasp elements in interlocked position, and others in a disengaged position.

Fig. 2 is a fragmental end view in perspective of the embodiment of Figure 1.

Fig. 3 is a plan view of an embodiment similar to Figure 1 showing a portion of the slide fastener broken away and the locking means in detail.

Fig. 4 is a plan view of a detail taken along line IV-IV of Figure 2; and

Fig. 5 is a view somewhat similar to Figure 4, but showing a section in perspective.

Referring to the drawing, numerals 1 and 1' represent tapes or stringers upon which an opposed series of fastener elements 3 and 3' are respectively assembled or mounted. For convenience in interlocking and disengaging these elements 3 and 3', a slide fastener 5 is mounted for cooperative association with each assembled series of them. As the fastener 5 is moved in one direction, it in turn, successively moves opposite elements of the opposed assemblies 3 and 3' into cooperative relationship, in order that adjacent or corresponding elements of the opposed assemblies interlock and thereby fasten edges of an opening together. If the slider 5 is moved in the opposite direction, the cooperating elements of the two assemblies or series are successively moved out of engagement, each element of one assembly is

separated from each element of the other, and the edges of the opening will be released and thus may be separated without any interference by the locking or fastening means.

It is now apparent that any spreading strain between the stringers of the openings 1 and 1' that originates above the point or points to which the slide fastener has closed the openings, as at 1a for example, will tend to move the slider backwards; and, this action, if not arrested, will progressively disengage the fastener elements 3 and 3' as above explained. To prevent the fastener elements from becoming disengaged except when desired, I have devised a novel and effective means or method for locking the slider to the fastener elements.

Although the fastener 5 may be readily built up from a plurality of plates imposed upon each other, yet in the illustrative embodiment, a single plate having a neck portion 9 has been employed. This plate may be first stamped out and then bent backwardly over itself at the neck spacing portion 9 to form opposed and spaced parallel portions or faces. These faces of the fastener plate 5 may be drilled out as at 12 as indicated in Figures 4 and 5 to receive a lug or rivet 10 (see Fig. 2), in order that they will be positively held and reinforced in position with respect to each other; the lug 10 may also act as an element guide, supplemental to the neck portion 9.

Since the upper and lower portions of the fastener plate 5 are substantially alike in design with the exception that the upper portion or face is provided with a ring 8 for supporting some suitable form of pull or hand grip; Figs. 4 and 5, although actually showing the lower portion, substantially show the upper portion thereof. As seen from Figs. 2 to 5 inclusive, the upper and lower portions of the plates of the slide fastener 5 are provided with longitudinally extending bent over or relatively short flanged edges 11 and 11', respectively, in order to form guideways for engaging side ends or faces of the fastener assemblies 3 and 3'. Due to the spacing between these upper and lower flanges 11 and 11' respectively, the stringers 1 and 1' are permitted to freely pass therethrough while the element assemblies 3 and 3' are being guided therethrough.

In order to prevent the slide 5 from being moved rearwardly and thus from disengaging the fastener elements 3 and 3' when a spreading strain is applied to stringers 1 and 1' at a point beyond the slider as at 1a, the front ends of each of the flanges of the upper and lower portions of the slide plate 5 may be provided with lug or toothlike prong members 6 and 6' which are inwardly flared or bent to project a short distance from the flanges 11 and 11' at right angles thereto into the path of an adjacent guideway and in

the direction of the opposite flange of the slider in order that each may be readily receivable between the individual elements of each of the assemblies 3 and 3'.

As is seen, the inner face of each toothlike prong 6 and 6', as explained above, is substantially at right angles to the flanges 11 and 11' and thus, taken longitudinally of the assembly, forms a positive engaging surface for clasping against a remote or near wide-face portion of one of the fastener elements (see Fig. 3) when it has been received therebetween, and taken laterally, lies adjacent an outwardly extending end portion, whereby rearward movement of the sliding element 5, independent of manual operation thereof, is positively prevented. The outer face of the locking portions or prongs 6 and 6' is somewhat rounded, convexly and inwardly curved, or beveled to permit the slider 5 to be readily moved forwardly and cause the remaining fastener elements to be moved into clasping engagement. These prongs 6 and 6', projecting inwardly from the sides of plate 5, may be termed forwardly closed and rearwardly open angle portions of their respective flanges 11 and 11'. Thus, when the stringers 1 or 1' are free from strain, the slider may be moved in either direction. The strain on the stringers as seen from Fig. 3 is what brings the prongs 6 and 6' very positively into cooperative engagement with the front and side edges of a given element of the assemblies 3 and 3'.

As will be noted from the drawing, and particularly, from Figure 3, the slider 5 has a neck portion of substantially constant width terminating in a body portion of outwardly diverging width. The flanges 11 and 11' of the neck and body portions are both planar, but the flanges of the neck are oppositely spaced in a parallel relation, while the flanges of the body are oppositely spaced and smoothly inclined outwardly to a point adjacent one end of the slider. The body portion of the slider 5 accomplishes the function of sliding and clasping together the elements of adjacent stringers; although the neck portion may also accomplish such function to a more limited extent, yet its chief function is holding together clasped remote or near elements of the assembly (taken longitudinally).

As shown, the extreme ends of the flanges 11 and/or 11' of the body portion of slider 5 are bent inwardly a substantial distance to form the prongs 6 and 6'. As a result, the outside ends of the elements 3 and 3' (taken transversely of the assembly) abut against and travel along the flanges 11 and 11', parallel thereto, once the prongs 6 and 6' have been cleared (since the elements are mounted on flexible stringers). The prongs 6 and 6' thus serve to initially shove the spread stringers toward each other and to then lock

immediate elements against a spreading force.

Although, as in Figs. 2 and 4, I have shown fastening prongs 6 and 6' positioned at the front ends of both flanges 11 and 11' of the upper and lower portions of the slider 5, yet I have found that the result is efficiently accomplished by employing upper and lower prongs on only one side of the slider as in Fig. 5. Of course, this mechanical detail will be governed by expediency, etc. That is, the location of one locking prong 6 or 6' or portion at one end of the guide flange 11' of an upper portion of the fastener and the one end of one opposite flange 11' of the lower portion of the fastener serves to provide the necessary locking protection.

In operation my device works substantially as follows: Assume that the slider has been moved to a point as indicated in Figure 3, in such a manner that a portion of the fastener elements are in engagement and the remaining portions are out of engagement. When in this position, in an ordinary fastener, if a spreading pressure or strain is exerted at point 1a of Figure 1, the tendency will be to force the slider to slide backwardly over the element assemblies 3 and 3', thereby disengaging them in the manner previously described when the pull 4 is manually operated. With my invention such action is rendered impossible as the strain will move stringers 1 and 1' and their associated assemblies 3 and 3' toward the flanged edges or prongs or corners 6 and 6' of the slider in such manner that the upper and lower prongs will move between the spacing of two of the fastener elements of a given assembly and against the side or outer end face thereof to halt rearward movement of the slider and to prevent further displacement of the fastener elements. This condition is maintained as long as the strain is present, and may be said to have been automatically brought about by the very forces which produce the strain. The slider 5 can be quickly unlocked however, by simply moving it in the proper direction in the usual manner in that the engagement between the locking prongs 6 and 6' and associated elements of the assemblies 3 and 3' is occasioned only when one attempts to unlock the assemblies independently of the slider. The outer portion of each prong is curved so that it may be readily knocked out of locking position by an adjacent front element when the slider 5 is moved forwardly by the pull 8. As a result, the elements 3 and 3' are moved back to a normal position and the slider 5 may be moved either forwardly or rearwardly without any difficulty.

My simple locking means with its ratchet-like action fills present needs for such a means, and in addition, presents features of economy and efficiency superior to anything now used in connection with such fasteners.

This device in no way interferes with the normal operation of the slider, but as soon as an abnormal condition arises, immediately becomes effective to accomplish the purpose for which it was intended.

While I have described but one embodiment of my invention, it will be apparent that many changes, modifications, substitutions, additions, and omissions or combinations thereof may be made in this device without departing from the spirit and scope of this invention as indicated in the appended claims.

What I claim as new and desire to secure by Letters Patent is:

1. In a slide fastener including a plurality of adjacent interlocking assemblies, the combination of a slider movably mounted on said adjacent assemblies for locking and unlocking said assemblies with respect to each other, said slider having an upper and lower portion whose side edges are flanged inwardly therefrom for forming a guideway for elements of the assemblies, said flanged edges having a planar guideway outline along their entire length, a prong extending inwardly from a front end of each portion adjacent the prong of the other portion of said slider for locking said slider against an unlocking movement produced by an opening strain upon the assemblies that is independent of manual operation of said slider.

2. In a slide fastener including a plurality of adjacent interlocking assemblies, the combination of a slider movably mounted on said assemblies for locking and unlocking them with respect to each other, said slider having upper and lower portions forming guideways for elements of said assemblies, said upper and lower portions having side edges flanged inwardly towards each other for limiting side travel of the elements of said assemblies, said portions having a neck portion terminating in a body portion, the flanges of said neck portion being in spaced and parallel relation with respect to each other for holding the elements of assemblies in a locked position and permitting them to slide therebetween while so locked, the sides of the flanged edges of said body portion inclining outwardly from the plane of the sides of the flanges of said neck portion and forming planar surfaces terminating in a prong extending inwardly into the path of the element guideway, said prong having an outwardly convex surface and having an inner surface substantially at right angles to the surface of an adjacent flange, so that said body portion will move separated assemblies towards each other, that said prong will initially move the assemblies toward each other, and so that said slider will be positively locked against a spreading movement of elements of the assemblies.

3. In a slide fastener including a plurality

of adjacent interlocking assemblies, said assemblies at one end terminating in a closely grouped set of elements, the combination of a slider movably mounted on said assemblies for locking and unlocking them with respect to each other, said slider having upper and lower portions provided with flanged edges extending inwardly towards each other and forming a guideway for the elements of the assembly, said slider including a neck portion having spaced and parallel side flanges and terminating in a body portion having spaced and planar and outwardly diverging side flanges, said body portion having a prong extending from one of its side flanges near the forwardly extending end thereof, said prong being positioned at right angles to its respective flange and having an outer face curved inwardly toward the guideway of said body portion, so that the remote ends of the elements of the assembly (taken transversely thereof) will be initially moved from a spread position towards a closed position by said prong when said slider is moved towards a closed position, that the remote ends of said elements will abut against and slide along parallel to the flanges of said neck and body portions of said slider, and so that said slider will be positively locked in position against an opening or spreading strain upon the assembly by an abutment of the inner face of said prong upon a remote face of an element taken transversely of the assembly.

In testimony whereof, I have hereunto subscribed my name this 29th day of May, 1931.

FRANK E. NODINE.
